Application filed July 10, 1930. Serial No. 36,322. Term of patent 3½ years.

To all whom it may concern:

Be it known that I, RUEL H. SMITH, a citizen of the United States of America, residing in North Attleboro, county of Bristol, State of Massachusetts, have invented a new, original, and ornamental Design for a Mesh Fabric, of which the following is a specification, reference being had to the accompanying drawing, forming a part thereof.

Fig. 1 is a top plan view; Fig. 2 is a side

elevation; Fig. 3 is a section of one of the wires, and Fig. 4 is an enlarged top plan view, showing my new design. The flattened wire used for the interwoven strands give somewhat of a beaded effect to the fabric.

I claim:

The ornamental design for a mesh fabric, substantially as shown and described.

RUEL H. SMITH.
